UNITED STATES PATENT OFFICE.

JOSEPH SCHMITTBERGER, OF WEST HOBOKEN, NEW JERSEY.

SASH-LOCK.

1,036,347.

Specification of Letters Patent. Patented Aug. 20, 1912.

Application filed February 7, 1912. Serial No. 675,913.

To all whom it may concern:

Be it known that I, JOSEPH SCHMITTBERGER, a citizen of the United States, and residing at West Hoboken, in the county of Hudson and State of New Jersey, have invented certain new and useful Improvements in Sash-Locks, of which the following is a specification, such as will enable those skilled in the art to which it appertains to 10 make and use the same.

This invention relates to window sash locks, and the object thereof is to provide an improved device of this class which is automatic in the operation of locking the 15 sashes together when the said sashes are moved into their closed position, a further object being to provide a device of the class specified which is simple in construction and operation, easily applied, and easily manipulated. With these and other objects in 20 view the invention is constructed and operates as hereinafter described and claimed.

The invention is fully disclosed in the following specification of which the accompanying drawing forms a part, in which the 25 separate parts are designated by suitable reference characters in each of the views, and in which:—

Figure 1 is a plan view of my improved 30 sash lock;—Fig. 2 a side view thereof;—Fig. 3 a section on the line 3—3 of Fig. 1, and showing the device in use, and;—Fig. 4 a section on the line 4—4 of Fig. 3.

In the drawing forming a part of this 35 specification I have shown at *a* the bottom part of the sash of a window having the usual bottom rail *a*², and at *b* the top part of the bottom sash of a window having the usual top rail *b*².

40 In the practice of my invention I provide a sash lock comprising a part *c* adapted to be secured to the bottom rail *a*² of the top sash, and a part *d* adapted to be secured to the top rail of the bottom sash, all as 45 shown in Fig. 3. The parts *c* and *d* taken together form a hollow truncated cone, and the part *c* is provided with a transverse rod *c*², and mounted in the back portion of the part *d* and centrally thereof is a spur wheel *e* having curved hook-shaped teeth *e*² all of 50 which extend in the same direction, and these teeth, in the operation of the device, are adapted to engage the rod *c*² as shown in Fig. 3, and lock the sashes together.

55 In the top of the part *d* is a radial slot *d*² over which is pivoted as shown at *d*³ a han-

dle lever *f* having a radially directed handle head *f*² and provided with a finger *f*³ which extends downwardly through the slot *d*² and the end of which is adapted to bear on the curved surface of one of the teeth *e*² of the wheel *e* as shown in Fig. 3, while the next adjacent tooth is adapted to bear on the back of said finger, and secured in the front bottom portion of the part *d* is a 60 spring *g* which bears on the front side of said finger as shown in said figure of the drawing.

The operation will be readily understood from the foregoing description when taken 65 in connection with the accompanying drawing, and the following statement: Suppose the bottom sash to be in a raised position, and it being desired to close the sashes and lock them together, the bottom sash is 70 moved downwardly, and in this operation the top front edge of the part *c* of the device strikes the back curved surface of one of the teeth *e*² of the wheel *e*, and the said wheel is turned to the right until the sashes 75 are moved downwardly, and in this position the next succeeding tooth engages the rod *c*² as shown in said figure and the sashes are locked together, and by 80 forcing the head of the lever *f* downwardly 85 into the position shown in said figure the sashes will be drawn tightly together at the top, this operation being occasioned by the end of the finger *f*³ of the lever *f* pressing on one of the teeth *e*² of the wheel *e*. And 90 when it is desired to unlock the sashes the head *f*² of the lever *f* is raised, and the top sash may be lowered, or the bottom sash 95 raised as will be readily understood.

It will be understood that the sashes may 100 be locked together either by raising the upper sash or by lowering the bottom sash, and at the end of either of these operations the position of the lever *f* is that shown in dotted lines in Fig. 3, and in order to lock 105 the parts and draw the sashes together the said lever is drawn down into the position shown in full lines in said figure, but the spring *g* may be made strong enough to hold the lever *f* in the position shown in full lines 110 in Fig. 3, under normal conditions, in which the entire operation of locking and drawing the sashes together would be automatic, but in order to unlock the sashes so as to permit of the downward movement of the upper sash, or the upward movement of the lower sash, the lever *f* must be raised

after which the movement of either of the sashes will rotate the wheel *e* and release the lock.

Having fully described my invention what I claim as new and desire to secure by Letters Patent is:—

1. A sash lock comprising a hollow casing composed of two parts one of which is adapted to be secured to the bottom rail of 10 the top sash and the other to the top rail of the bottom sash, the part which is adapted to be secured to the bottom rail of the top sash being provided with a transverse rod, and the part which is adapted to be secured 15 to the top rail of the bottom sash being provided with a spur wheel mounted in a plane transversely of said rod and provided with hook shaped teeth which operate in connection with said rod and a spring operated lever 20 mounted in the top of the last named part and provided with a downwardly directed finger adapted to bear on the backs of said teeth.

2. The combination with the sashes of a window, of a lock comprising a part secured to the bottom rail of the top sash, and a part secured to the top rail of the bottom sash, the first named part being provided with a transverse rod, and the last named part with a spur wheel mounted in a plane transversely of said rod and provided with hook shaped teeth which operate in connection with said rod, and the last named part being also provided with a spring operated lever which is pivoted in 30 the top portion thereof and provided with a finger adapted to bear on the backs of said teeth.

In testimony that I claim the foregoing as my invention I have signed my name in 40 presence of the subscribing witnesses this 5th day of February 1912.

JOSEPH SCHMITTBERGER.
